E. H. JONES

GOLF TEE

Filed July 31, 1926

INVENTOR
Eleanor H. Jones.
BY
John H. Alliand
ATTORNEY

UNITED STATES PATENT OFFICE.

ELEANOR H. JONES, OF BOSTON, MASSACHUSETTS.

GOLF TEE.

Application filed July 31, 1926. Serial No. 126,162.

This invention relates to golf tees, and has for an object the provision of a golf tee which can be used frequently without being broken or deformed; and which possesses 5 also the desirable advantages of a tee that obviates any risk of injury to the various clubs used by the player in driving the ball from the tee in the several plays for which such a tee is needed; is readily adjustable by insertion into the ground to different depths in order to hold the ball at the different 10 heights required; and is so formed that it affords a firm support for the ball without interfering with ready clearance of the ball 15 from the tee under the action of any club used, but which tends to leave the ground if struck by a club in play, rather than be broken or bent by the force of the stroke.

Another object is to provide a tee which 20 cannot be knocked off the teeing ground, comprising a brace of tee members, respectively having ball-supporting heads and shanks for insertion into the ground, being connected by a leash, so that either may be 25 used to support a ball, and each serves as an anchor for the other, whereby the twin tee thus constituted is retained in position to be secured immediately after a stroke is 30 played.

Still a further object is to provide a golf tee having a shank of flat metal with its upper end bent over to form a head portion, and provided with a leash composed of a metal cable attached firmly to the head, the 35 region of attachment being surrounded by resilient material moulded to form a ball-supporting head which completely encloses and protects the metallic parts so as not to permit injury to a club.

A further object of the invention is to 40 provide a tee of novel shape, having a base portion of inverted frusto-conical shape, so that it permits insertion to a greater or less extent into the ground of a soft nature, but 45 with increasing resistance as the depth of insertion increases; the top of the tee being formed in a frusto-conical shape of reversed taper, and having a ball supporting depression formed in its upper face.

Another object of the invention is to 50 provide a tee having a ball supporting part of light colored material, and a shank of bright stainless, enamelled or painted metal, so that the tee is not only weatherproof but can also 55 be readily found if displaced by the stroke,

and will not be easily overlooked if left in the ground.

The above objects and others are fully described in the specification and are illustrated in the drawings and pointed out in 60 the claims.

In the drawings,

Fig. 1 is a view partly in section and partly in elevation of a brace of twin golf tees in the construction of which my invention has 65 been embodied.

Fig. 2 is a view in perspective of one of the tees, omitting the ball-supporting head to show the preferred mode of attachment 70 of the leash.

Fig. 3 is a view in elevation of a modified form of blank for the shank of a tee.

Fig. 4 is a view similar to Fig. 1 of a brace of tees formed with the modified shank shown in Fig. 3. 75

Fig. 5 is a plan view of one of the modified tees, isolated.

In accordance with an important feature of the invention, I provide a brace of tees, as shown in Fig. 1, and each of which is 80 designated by the reference numeral 1, connected by a leash 2 and either of which may be used in play, the other serving as an anchor, so that if the tee is driven from the ground in play, it will be retained by the 85 leash anchor of its companion tee, and can be readily picked up, or if desired it may be easily replaced and another ball placed upon it and driven from it or another ball may be placed upon, and driven from the 90 companion tee, thus insuring maintenance of identical conditions for the play of successive balls.

Such a brace of tees gives to a player the same degree of confidence in playing that is 95 secured ordinarily only by the use of the conventional destructible tee formed of sand or like material, of which one has to be shaped for each stroke, with the incidental irregularities of shape and uncertainties of 100 operation that attend the employment of these adventitious sand tees even when made with the assistance of moulds. In spite of these well recognized disadvantages of the sand tees, their use by the most skillful 105 players has persisted, for the reason chiefly that none of the substitutes of which many have been devised, affords the respective advantages yielded by the novel tee herein disclosed. 110

The twin tees may be of any suitable shape and structure, respectively, and I have illustrated as the now preferred form of tee a structure having certain advantageous features which constitute another important object of this invention.

In the illustrated embodiment, the part designated by the reference number 1 in Fig. 1 is the ball-supporting member of a golf tee, which may be made of any suitable material and which preferably has its base formed substantially in the inverted frusto-conical shape illustrated at 3, for convenience in manufacture. The top of the tee may also be frusto-conical in shape and may have a ball-supporting rim, if desired, as indicated at 4.

I prefer to make this ball-supporting member of resilient material, such as india rubber, to avoid injury to the clubs used and to the tee, and I prefer also to use a light colored material, for the sake of visibility. In order to aid in securing the desired erect position of the tee in the ground, I prefer to mould the ball-supporting part of the tee upon a shank 5 having a bayonet point 6 adapted to be inserted in the ground, the shank portion being preferably flat, in order to facilitate its insertion in the cracks or crevices often found in teeing grounds when the latter are made of clay, as is often the case in southern countries. This shank is preferably made of bright, stainless metal or enamelled or painted metal, both for the sake of visibility and to avoid the unpleasant appearance which comes from the presence of rust.

In accordance with another important feature of the invention, I provide a very strong leash 2 for the tee, and also provide for a very firm attachment between the leash and tee, and between the ball-supporting part of the tee and the shank thereof; and in pursuance of this object I have shown the leash 2 as made of a metal strand or cable, the end 7 of which is united integrally with the shank as shown at 8 in Fig. 2 by splitting the upper end of the shank to form a cleft within which the end 7 of the leash is embraced and held firmly. The split portion is preferably bent around as indicated to constitute a head loop open at the sides to give access to the material of the ball-supporting head, so that when the material is moulded upon this head loop of the shank, as shown in section at the left-hand side of Fig. 1, the material enters the head as indicated at 9 and unites the ball-supporting part to the shank and to the leash, completely surrounding the region of attachment between the leash and the head of the shank, thereby preventing any injury to a club by the tee if the club strikes the tee, and likewise preventing any injury to the tee by such contact of the club, as the resilient

material will receive the entire force of the impact, and has been found in practice to survive many vigorous blows.

The cable is preferably covered with a sheath 10 of protective material, such as the braided silk covering indicated at 10 in Fig. 2, and this covering may be conveniently colored green, which diminishes its visibility and so does not tend to distract the attention of the player, who may however derive a certain desirable indication of direction from the presence of the leash between the twin tees.

Modifications of the structure and material may be adopted as found suitable and desirable, and I have illustrated one such modification in Figs. 3, 4, and 5. In this modification, the shank may be straight, as at 11 or may have a somewhat wavy character, as at 17, with a bayonet point, and has its upper end bent over to form an eye 12 from which the central part 13 is bent in an opposite direction, to constitute with the eye 12 a laterally extending head as shown clearly at the left-hand portion of Fig. 4, where a complete tee is shown in vertical section with the shank in elevation.

The eye 12 may be desirably used as a means for the attachment of one end of a leash 14 which may be formed as a cable secured to the eye before the ball-supporting head is moulded thereupon, and the leash may desirably have a cover 15 of rubber or other suitable material, as already described with reference to the leash 2.

The ball-supporting part 16 may correspond in general contour and arrangement with that already described with reference to the structure shown in Fig. 1, or may be of any suitable contour.

I claim:

1. A golf tee comprising a brace of ball-supporting members each having a ball-supporting head and a shank for insertion into the ground, said shanks having their upper portions connected by a leash, and said ball-supporting heads being molded upon, and completely surrounding the attachment between said shanks and said leash.

2. A golf tee comprising a brace of ball-supporting members each having a metal shank for insertion into the ground, said shanks having their heads connected by a leash of metal cable provided with a non-metallic covering and said members having ball-supporting heads molded upon the heads of said shanks and the portions of said leash attached thereto.

3. A golf tee comprising a brace of ball-supporting members each having a metal shank for insertion into the ground, said shanks having their heads connected by a leash of metal cable covered with braided silk and said members having ball-supporting heads formed of rubber molded upon

the heads of said shanks and completely surrounding the attachments between said heads and said leash.

4. A golf tee comprising a ball-supporting head, a shank for insertion into the ground, and a leash attached to the upper portion of said shank, said ball-supporting head being molded upon, and completely surrounding, the attachment between said shank and said leash.

5. A golf tee comprising a ball-supporting head, a metal shank for insertion into the ground, and a leash of metal cable attached to the head of said shank, and said ball-supporting head being formed of rubber molded upon the head of said shank and the portion of said leash attached thereto.

6. A golf tee comprising a ball-supporting part molded of resilient material upon a shank of metal having an attaching head

formed by splitting the upper portion of said shank, and bending said split portion at an angle to the shank, and a leash secured in said split head portion and extending outwardly therefrom through said 25 molded material.

7. A golf tee comprising a metal shank having one end split and bent to form a head, a leash secured in said split head, and a ball-supporting part molded around said 30 head and completely enclosing said region of attachment.

8. A golf tee comprising a ball-supporting head of light-colored resilient material molded upon a shank of bright, stainless 35 metal and provided with a metal leash covered with green fabric.

In testimony whereof, I have signed this specification.

ELEANOR H. JONES.
